(57) **CLAIM**

The ornamental design of a storage and transportation device, as shown and described.

DESCRIPTION

FIG. 1 is a perspective view of a first embodiment of the device;

FIG. 2 is a top view of the first embodiment of the device;
FIG. 3 is a front view of the first embodiment of the device;
FIG. 4 is side view of the first side of the first embodiment of the device;

FIG. 5 is a side view of a second side of the first embodiment of the device;

FIG. 6 is a top view of a second embodiment of the device;
FIG. 7 is a front view of the second embodiment of the device;
FIG. 8 is a side view of the second embodiment of the device; and,

FIG. 9 is a back view of the second embodiment of the device. The broken lines in the drawings are included for the purpose of illustrating portions of the storage and transportation device and form no part of the claimed design.
